UNITED STATES PATENT OFFICE.

JOSEPH P. KEEGAN, OF NEWARK, NEW JERSEY.

SOUNDING DEVICE.

Application filed January 10, 1922. Serial No. 528,326.

To all whom it may concern:

Be it known that I, JOSEPH P. KEEGAN, a citizen of the United States, and resident of Newark, in the county of Essex and State of New Jersey, have invented a new and Improved Sounding Device, of which the following is a full, clear, and exact description.

My invention relates to a sounding device, and aims to provide certain new and useful 10 improvements in connection with a toy of this character.

It is an object of the present invention to provide a device of the character stated which may be readily and economically constructed, and in which the working parts 15 will be reduced to a minimum, the said device being capable of being manufactured at a nominal figure, and being extremely efficient in action.

20 Still another object of the present invention is the construction of a sounding device which may be operated by a child and without any danger of injury to the operator.

25 Still further objects of this invention will appear in the annexed specification taken in connection with the drawings, which latter illustrate one practical embodiment of the same, and in which;

30 Figure 1 is a bottom plan view of a sounding device embodying my improved construction.

Figure 2 is a top plan view thereof.

35 Figure 3 is an enlarged sectional side elevation, and

Figure 4 is a transverse sectional view taken along the line 4—4 and in the direction of the arrows indicated in Figure 3.

It will be seen in these views that the reference numeral 5 indicates the casing of the 40 device which may be in any desirable shape and material, and which has a handle 6 rotatably attached to its body in a manner hereinafter described, so that the operator

45 may grasp the handle, and by virtue of the same being disposed at a point adjacent one end of the casing the latter may be whirled from the handle.

As has been shown in Figure 3 the interior 50 of the casing 5 is preferably divided by means of the baffle plate 7 having one of its ends terminating adjacent a discharge opening 8, its opposite end being disposed to provide a space 9 and a further space suitable for the reception of an operating spool 55 or drum 10. Thus if a coil of material 11 is

disposed in the space 9, and the ends of this coil are passed around the spool 10 and engaged by the same by means of a suitable frictional surface 12 the end of the material 60 being extended along the baffle 7 and through the discharge opening 8, it will be understood that an operator may whirl the casing 5 by means of the handle 6 and if the latter is operatively attached to the spool 10 65 it will be obvious that the spool will be fed from the coil 11 around the spool 10 and thence along the baffle 7 and out of the discharge opening 8.

Now with a view of establishing this connection it will be noted, reference being had to Figures 1 and 3, that the handle 6 has a suitable type of gear 13 attached to its body and this gear meshes with a second gear 14 attached to the spool 10. Thus the 70 result desired will be achieved. Also by securing a ratchet wheel 15 to the body of the handle 6 and by positioning a spring pressed hammer 16 adjacent to the ratchet wheel it will be obvious that an operator upon actuating the device in the manner aforementioned, will produce a periodic retraction and release of the hammer 16.

Further it will be noted that the coil of material 11 is preferably in the nature of a 80 strip of caps, and a portion of the baffle 7, at a point preferably intermediate the space 9 and drum 10 is enlarged to provide an anvil 17 and thus it will be understood that by means of the operation of the hammer afore- 85 described the caps will be exploded.

From the foregoing it will be appreciated that all of the objects of this invention are accomplished in that an easy and simple device is constructed, and may be operated by 90 a child without any fear of danger to the operator, although a great amount of noise will obviously be produced by the successive explosions resulting when the device is operated.

Finally it will be understood that numerous modifications of structure might readily be resorted to without in the least departing from the scope of my claims; which are;

1. A sounding device including a casing, 105 an anvil within said casing, a hammer also within said casing, means for feeding a detonating strip, means for actuating said hammer, and means for actuating the two means last-mentioned periodically.

2. A sounding device including a casing, 110 cap detonating means within said casing,

and a handle rotatably secured to said casing, and operatively connected to said cap detonating means the detonating means having associated therewith co-operant fixed 5 and movable parts for feeding a detonating strip, the latter part being operatively connected to the handle.

3. A sounding device including a casing, cap detonating means within said casing, 10 a handle rotatably secured to said casing, said detonating means including a hammer periodically operated by the handle, means also periodically operated by the handle for feeding a detonating strip, and operative 15 connections from the handle to said two means whereby the hammer operates a plurality of times for each operation of said feeding means.

4. A sounding device including a casing, 20 a baffle within said casing, a portion of said baffle providing an anvil, a spring pressed hammer for co-operating with said anvil, and means for retracting and releasing said hammer.

25 5. A sounding device including a casing, a baffle within said casing, a portion of said baffle providing an anvil, a spring pressed hammer adapted to cooperate with said anvil, means adapted to operatively support 30 a strip of caps and guide said strip to pass over said anvil, means for operating said last named means, and means for alternately releasing and retracting said hammer.

6. A sounding device including a casing having an opening, a baffle within said casing to provide an anvil and a space for the reception of a strip of caps, a spool rotatably supported within said casing, a spring pressed hammer for cooperating with said anvil, said strip passing around said spool, 40 and means for rotating said spool and effecting a retraction and release of said hammer.

7. A sounding device including a casing having an opening, a baffle within said casing to provide an anvil and a space for the 45 reception of a strip of caps, a spool rotatably supported within said casing, a spring pressed hammer for co-operating with said anvil, said strip passing around said spool, a handle rotatably secured to said casing, a 50 ratchet wheel connected to said handle, for co-operating with said hammer, said handle being connected to said spool.

8. A sounding device including a casing having an opening, a baffle within said casing to provide an anvil and a space for the reception of a strip of caps, a spool rotatably supported within said casing, a spring 55 pressed hammer, said strip passing around said spool, a handle rotatably secured to said casing, a ratchet wheel connected to said handle for co-operation with said hammer, said spool being also connected to said handle and carrying a frictional device for feeding said strip.

JOSEPH P. KEEGAN.
